UNITED STATES PATENT OFFICE.

FREDERICK SKELTON, OF HAMILTON, ONTARIO, CANADA.

HANDLE FOR SHOVELS, &c.

No. 888,541.

Specification of Letters Patent.

Patented May 26, 1908.

Application filed June 20, 1907. Serial No. 379,856.

To all whom it may concern:

Be it known that I, FREDERICK SKELTON, a citizen of the United States, residing at Hamilton, in the Province of Ontario and 5 Dominion of Canada, have invented certain new and useful Improvements in Handles for Shovels, &c., of which the following is a full, clear, and exact description.

My invention relates to improvements in 10 handles for shovels, spades, and other tools in which there is an elongated or vertical member the upper end of which is bifurcated and a transverse hand member fitted between the arms of the said bifurcated end.

15 The objects of my invention are to provide a handle wherein the several parts are neatly fitted together and rigidly held; wherein means are provided to materially strengthen the handle around the commencement of the 20 bifurcated part thereof and prevent splitting thereof; and finally to provide a handle which shall be strong, durable and yet comparatively light and easily handled.

With these objects in view my invention 25 consists in the features hereinafter described and claimed.

Reference is hereby made to the accompanying drawing, of which

Figure 1 is a front elevation of the upper 30 end of the handle; Fig. 2 is a side elevation of the same; Fig. 3 is a view similar to Fig. 1, partly in section; Fig. 4 is a perspective view of the socket member for uniting the transverse member to one of the arms of the bifurcated end of the handle; and Fig. 5 is a sectional detail view of said socket.

As shown in the drawing, the improved handle comprises an elongated member 1, the upper end of which is bifurcated to form 40 arms 2, 2. At the point where the bifurcation begins, a rivet 3, is placed to prevent splitting of the member 1, and the thickness and cross section of the member 1 is greater around the rivet 3 than at other points of the 45 handle, whereby its strength is unimpaired by the removal of the material to form the rivet hole. The arms 2 are of diminishing width, as shown in Fig. 2, and upon their ends are fitted the socket members 4, which, 50 as shown, are shells formed with upper and

lower openings 5 and 6 respectively through which the ends of the arms 2 extend. The opening 6 is slightly larger than the opening 5, whereby a socket is formed which tapers in the same degree as the end of the arm 2, so 55 that the socket members 4 may be forced into firm engagement with the ends of said arms. Each socket member 4 also comprises a flat ring 7, which is adapted to receive the reduced end 8, of the transverse 60 hand member 9 (see Fig. 3), so as to prevent any possible displacement of said transverse member and an outer wall or web 11 extending continuously from one part of the ring 7 to another diametrically opposite part of the 65 same. A bolt 10 is then inserted to bind the sockets 4, arms 2, and hand member 9 firmly together, the ends of said bolt being upset to form a rivet which engages the wall 11 of the socket member 4. The hand member 9 is 70 preferably of wood and the grain runs longitudinally thereof, which gives it maximum strength, and also makes it easy for the hand.

Having now described my invention, what I claim, is:

1. A handle for shovels and the like comprising an elongated member having a bifurcated end the arms of which are tapered, a transverse hand member between the ends of said arms, and a pair of socket members each 80 formed with a ring into which one end of said transverse member is fitted, and a web with upper and lower openings 5 and 6 of different size into which is wedged one of said tapered arms, said web extending continuously around said arm from one side of the ring to the other.

2. A handle for shovels and the like comprising an elongated member having a bifurcated end, the arms of which are tapered, a 90 transverse hand member between the ends of said arms, a pair of socket members each formed with a ring into which one end of said transverse member is fitted, and a web with upper and lower openings 5 and 6 of different 95 size into which is wedged one of said tapered arms, said web extending continuously around said arm from one side of the ring to the other, and a bolt passing through said webs, arms and hand member.

75

100

3. In a handle for shovels and the like, a socket member consisting of a shell having upper and lower openings 5 and 6, said lower opening being larger than said upper opening, whereby said openings are adapted to receive a tapered member, a socket adapted to receive a member at right angles to that received by said openings 5 and 6, and a wall

11 connecting diametrically opposite parts of said socket. 10

In witness whereof, I subscribe my signature, in the presence of two witnesses.

FREDERICK SKELTON.
